UNITED STATES PATENT OFFICE.

ANDREW V. ERVING, OF DETROIT, MICHIGAN.

DESIGN FOR A BIRD-CAGE STAND.

Application filed March 20, 1922. Serial No. 1,272. Term of patent 3½ years.

To all whom it may concern:

Be it known that I, ANDREW V. ERVING, a citizen of the United States, residing at 3652 Meldrum Avenue, in the city of Detroit, county of Wayne, and State of Michigan, have invented a new, original, and ornamental Design for a Bird-Cage Stand, of which the following is a specification,

reference being had to the annexed drawing, forming part thereof.

The figure is a side elevation of my bird cage stand, showing my new design.

I claim:

The ornamental design for a bird cage stand as shown.

ANDREW V. ERVING.
